JOSEPH H. ERNEST HOULE, OF WORCESTER, MASSACHUSETTS

SELECTIVE CALENDAR

Application filed February 26, 1931. Serial No. 518,466.

This invention relates to a calendar particularly designed for use by firemen or other persons employed on a fixed working cycle. Very many firemen work under the so-called "double platoon" system, under which they have two days of day-time duty, one long period of twenty-four hour duty, two days of night duty, and one day off, making a working cycle of six days.

It is very frequently desirable for a particular fireman to be able to determine what his duties will be on a selected future date but this is rather laborious when working on the involved "double platoon" or other similar system.

It is the object of my invention to provide a calendar which may be manipulated to selectively indicate the future dates on which specific duties are to be performed. Or, conversely, the calendar may be used to indicate the duties to be performed on a selected future day.

My invention further relates to arrangements and combinations of parts which will be hereinafter described and more particularly pointed out in the appended claim.

A preferred form of my invention, together with certain modifications thereof, are shown in the drawing, in which

Fig. 1 is a front elevation of my improved calendar;

Fig. 2 is a detail sectional view, taken along the line 2—2 in Fig. 1;

Fig. 3 is a front view of a modified monthly disc, and

Fig. 4 is a fragmentary view of a further modification.

Referring to Figs. 1 and 2, my improved calendar comprises a card 10 and a disc 11, pivotally secured together in a convenient manner as by an eyelet 12. The disc 11 is preferably held lightly by friction between the face of the card 10 and the under surface of the end flange of the eyelet 12, so that the disc may be readily set in a desired angular position and will be frictionally held against displacement.

The surface of the card 10 is divided to provide a number of segments 15, equal in number to the number of days in the working

cycle for which the calendar is to be used. The calendar shown in the drawing is arranged for the usual "double platoon" cycle of six days, as previously described, and consequently there are segments 15 arranged around the axis of the disc 11 and of equal angular extent.

The disc 11 is similarly divided into the same number of segmental spaces 17, which spaces are designed to receive abbreviations for the names of the months, arranged according to a system to be described.

Each of the segments 15 of the card 10 contains consecutive numerals from one to thirty-one, arranged in a number of concentric segmental spaces equal to the number of days in the working cycle. In the usual "double platoon" cycle, the numerals are thus arranged in six concentric segmental spaces, as shown in Fig. 1. The numerals are also arranged consecutively in radial columns, but with the series starting from a different segmental space in each different segment 15.

For instance, in the segment 15 at the right in Fig. 1, the numeral 1 appears in the outer segmental space, and in each successive segment taken in an anti-clockwise direction the numeral "1" appears one space nearer the center. The order in which the segments are arranged may be varied, it being merely necessary that the numeral "1" shall appear in each one of the segmental spaces in some one of the segments.

In the drawing, figures of different face have been utilized to indicate different kinds of duty. For instance, the outer circle of light faced figures indicates days off. The next two circles of heavy faced figures indicate day-time duty. The circle of double line figures indicate twenty-four hour duty and the two circles of white figures on a black background indicate night-duty.

The names of the month are applied to the segment 17 on the disc 11 in reference to the different arrangements of numerals in the segments 15 and also in reference to the number of days in the preceding month.

For instance, assuming that the segment 15a indicates the correct calendar for a given man for July having thirty-one days, it will

be evident that August 1st will come on the 3rd segmental space, counted from the outside, as indicated in segment 15^b, and accordingly the abbreviation for August appears in 5 the next segment anti-clockwise to the abbreviation for July. August also having thirty-one days, the first day of September will evidently be in the twenty-four hour circle and consequently will be found in the segment 10 15^c. As there are only thirty days in September, the first day of October will also be in the twenty-four hour circle and October will accordingly be indicated in the same segmental space as September. The 15 other months are similarly distributed as shown in Fig. 1.

With the numerals and names of the months arranged as described, the calendar is used as follows:—A certain fireman or other person 20 knows that on February 6, he was having a "day off" and he wishes to know what he will be doing on November 17th. He sets the disc 11 so that the segment marked "Feb." corresponds with the segment 15^a in which 25 the figure 6 appears in the outer or "Days Off" circle. He then finds that the abbreviation for November is opposite the segment 15^d, from which he discovers that on November 17 he will be doing day-time duty, as the 30 figure 17 appears on the third circle inward from the outside.

By a similar procedure, he can discover that on August 10 he will be doing night duty, and that on October 13 he will be on twenty- 35 four hour duty, while on April 19 he will have a day off.

When the disc 11 is once set correctly with respect to the card 10, the duties on any future date can be determined at a glance, so long 40 as the fireman follows the regular working cycle without change or interruption. If any change is made in the cycle, the device can be readily re-set for the new conditions, or it can be reset for use by any other party having 45 a different day off.

When the calendar is to be used on Leap Year, in which February has an extra day, a slight re-arrangement of the monthly disc is necessary, as indicated in Fig. 3, otherwise 50 the calendar is unchanged so long as the number of days in the working cycle remains the same.

If a cycle of five days is used instead of six, the card and disc would be divided into 55 five segments, and the numerals would be arranged in five concentric circles instead of six, with the proper revision in the location of the months on the disc 11.

While I have shown the names of the 60 months on the disc and the numerals on the card, it will be obvious that the arrangement can be readily reversed, as indicated in Fig. 4, with the numerals on the disc and the names on the card.

Having thus described my invention and

the advantages thereof, I do not wish to be limited to the details herein disclosed, otherwise than as set forth in the claim, but what I claim is:—

A selective calendar for use in determining future dates under a fixed working cycle of six days having four different kinds of twenty-four hour periods each with distinguishing working characteristics, said calendar comprising a card and a dial pivoted thereon, the faces of said card and dial being each divided into a number of circular segments of equal angular extent and equal in number to the number of days in said working cycle and said parts constituting 70 month and numeral members, the segments on the month member each bearing the name of one or more selected months and the segments on the numeral member each bearing consecutive numerals from one to thirty-one 75 inclusive, said numerals being arranged in a plurality of concentric annular spaces on each segment of said numeral member and the number of said concentric annular spaces on each segment being equal in number to the 80 number of days in the working cycle and to the number of segments in each of said members, said numerals being also arranged consecutively in substantially radial columns in 85 said segments, with each different concentric space containing numerals indicating days 90 having the same working characteristics, the numeral "one" in each numerical series being positioned in an annular space on its segment 95 which is at a distance from the dial axis different from the space containing the numeral "one" in any other segment, and the name of 100 each month being displayed in a segment on the month member which for any relative angular setting of said members contains the numeral "one" in that annular space which is 105 next in consecutive order to the annular space occupied by the numeral indicating the last day of the preceding month, for all years except leap year.

In testimony whereof I have hereunto affixed my signature.

JOSEPH H. ERNEST HOULE.
